CURTAIN ENSEMBLE

Amanda E. Liddell, 901 Jefferson Ave., Brooklyn 21, N.Y.

Filed May 8, 1963, Ser. No. 74,804

Term of patent 7 years

(Cl. D21—6)

FIG. 1

FIG. 2

FIG. 1 is a front elevational view of a curtain ensemble embodying my new design; and

FIG. 2 is a side elevational view thereof shown in FIG. 1.

My curtain ensemble design comprises a pair of sash curtains and a pair of tied-back top curtains, each curtain being formed of a series of over-lapping, embroidered, scalloped strips stitched together, substantially along their upper edges, in combination with matching scalloped tie-back and pendant pieces, all as shown.

I claim:

The ornamental design for a curtain ensemble, as shown and described.
